UNITED STATES PATENT OFFICE.

WILLIAM HUBELI WALDRON, OF NEW BRUNSWICK, NEW JERSEY,
ASSIGNOR TO JOHN WALDRON COMPANY, OF NEW BRUNSWICK,
NEW JERSEY.

REELING-MACHINE FOR PAPER OR OTHER FABRICS.

SPECIFICATION forming part of Letters Patent No. 795,079, dated July 18, 1905.

Application filed December 20, 1904. Serial No. 237,659.

To all whom it may concern:

Be it known that I, WILLIAM HUBELI WALDRON, a citizen of the United States, and a resident of New Brunswick, in the county of 5 Middlesex and State of New Jersey, have invented a new and Improved Reeling-Machine for Paper or Other Fabrics, of which the following is a full, clear, and exact description.

The invention relates to reeling-machines 10 for paper or other fabric, such as shown and described in the Letters Patent of the United States No. 570,355, granted to me October 27, 1896.

The object of the present invention is to 15 provide a new and improved reeling-machine arranged to insure automatic reeling or winding up of paper or other fabric, to allow convenient adjustment of the winding-roll, and to permit bringing the paper under proper 20 tension.

The invention consists of novel features and parts and combinations of the same, as will be more fully described hereinafter and then pointed out in the claims.

25 A practical embodiment of the invention is represented in the accompanying drawings, forming a part of this specification, in which similar characters of reference indicate corresponding parts in all the views.

30 Figure 1 is a side elevation of the improvement. Fig. 2 is an enlarged side elevation of the tension device. Fig. 3 is an enlarged side elevation of the driving-roll and winding-roll, the bearing of the latter being shown

35 in section. Fig. 4 is an enlarged sectional plan view of one of the eccentric bearings for the winding-roll. Fig. 5 is an enlarged sectional side elevation of the same on the line 5 5 of Fig. 4, and Fig. 6 is a detail view 40 of the lower portion of the U-shaped frame.

On a suitably-constructed frame A is journaled a driving-roll B, connected with other machinery for imparting a rotary motion to the said driving-roll, to rotate the winding- 45 roll C, arranged directly above the driving-roll and on which the paper D or other fabric is wound. The winding roll or core C is jour-

naled at each end in a bearing E, (see Figs. 3 and 4,) provided with a trunnion E', fitting an eccentric bore in a box F, mounted to slide 50 vertically in guideways A', forming part of the main frame A. On each box F is arranged a handle F', adapted to be taken hold of by the operator for turning the box F, so as to bring the winding-roll C in proper relation 55 to the driving-roll B, and after proper adjustment is made the trunnion E' and the box F are fastened together by a suitable set-screw F², as indicated in Figs. 1 and 5.

Each of the bearings E is provided with 60 an upwardly-extending ear E², engaged by a rod G, extending upwardly and mounted to slide in suitable bearings on the main frame A, the upper end of each rod carrying a weight G' to hold the winding-roll C with suf- 65 ficient friction in contact with the driving-roll B for the latter to rotate the winding-roll C. On each bearing E is also secured a handle E³, adapted to be taken hold of by the operator for lifting the winding-roll C when- 70 ever it is desired to do so. On the bearings E are also formed horizontally-extending ears E⁴, to which are secured the side arms of a U-shaped frame H, having its middle portion engaged by a treadle H', fulcrumed on the 75 main frame A and under the control of the operator. Thus when it is desired to slightly lift the winding-roll C for placing the paper in position on the winding-roll it is only necessary for the operator to press the treadle 80 H' to accomplish the desired result.

When the paper has been wound upon the winding-roll C and the latter has reached an uppermost position in the guideways A', then the roll of paper can be temporarily sup- 85 ported by supporting-arms I, fulcrumed on the main frame A and adapted to swing under the boxes F. Each of the arms I is connected by a link I' with a treadle mechanism I² to enable the operator to swing the arms I 90 under the boxes F whenever it is desired to support the paper or roll previous to its removal from the machine.

In order to give the desired tension to the

paper D during the reeling operation, the following device is provided: The paper D as it comes over a rack J to the machine passes first to a tension-roller K, then beneath the same to a tension-roller K', then beneath the latter to a tension-roller K², and then beneath the roller K² to a tension-roller K³, to pass from the latter over an intermediate pulley L, to finally pass onto the driving-roll B. Now the tension-rolls K and K' form one pair, mounted on yokes or arms N, and the tension-rolls K² and K³ form a pair mounted on arms or yokes N'. The yokes N and N' are secured on shafts N² and N³, respectively, journaled in suitable bearings held on the main frame A, and on the said shafts N² and N³ are secured gear-wheels O and O', in mesh with a gear-wheel O², secured on a shaft O³, journaled in suitable bearings on the main frame A. On the shaft O³ is secured a hand-wheel O⁴, adapted to be turned by the operator to rotate the shaft O³ and gear-wheel O², so that the latter simultaneously rotates the gear-wheels O and O' to turn the shafts N² and N³, and thereby give a simultaneous swinging motion to the yokes N and N' to bring the pairs of tension-rolls K K' and K² K³ into an angular position (see dotted lines, Fig. 2) for giving the desired tension to the paper D previous to the latter passing onto the idler-pulley L and driving-roll B. When the desired tension has been given to the paper D, then the parts of the tension device are locked in place, and for this purpose the shaft O³ is provided with a ratchet-wheel P, engaged by a pawl P', fulcrumed on the main frame A. (See Fig. 1.)

By having the two pairs of tension-rolls adjusted simultaneously it is evident that a very strong tension can be given to the paper to prevent slipping of the same and to insure a compact winding up of the paper on the winding roll or core C, it being understood that an even winding of the paper on the roll C is insured by properly adjusting the roll C by the use of the eccentric boxes F, as previously explained.

Having thus described my invention, I claim as new and desire to secure by Letters Patent—

1. In a reeling-machine, the combination with a driving-roll, of a winding-roll surmounted upon the driving-roll and adapted to be rotated by it, movable bearings in which the winding-roll is mounted, each bearing being provided with an upwardly-extending ear, a rod engaging each of said ears, a weight carried by each rod, and a foot-controlled

means for raising the winding-roll and the said weights.

2. In a reeling-machine, the combination with a driving-roll, of a winding-roll surmounted upon the said driving-roll and adapted to be rotated by it, bearings for the shaft of the winding-roll to turn in, the bearings having trunnions, handled boxes having eccentric bores for the trunnions to turn in, vertical guideways for the boxes to slide in, vertical rods connected at their lower ends with ears on the said bearings, and weights carried at the upper ends of said rods. 70

3. In a reeling-machine, the combination with a driving-roll, of a winding-roll surmounted upon the said driving-roll and adapted to be rotated by it, bearings for the shaft of the winding-roll to turn in, the bearings having trunnions, handled boxes having eccentric bores for the trunnions to turn in, vertical guideways for the boxes to slide in, vertical rods connected at their lower ends with upwardly-extending ears on said bearings, a weight attached to the upper end of each rod, a handle on each bearing for lifting the winding-roll, and means for supporting the raised winding-roll in a raised position. 75

4. In a reeling-machine, the combination with a driving-roll, of a winding-roll surmounted upon the said driving-roll and adapted to be rotated by it, bearings for the shaft of the winding-roll to turn in, the bearings having trunnions, handled boxes having eccentric bores for the trunnions to turn in, vertical guideways for the boxes to slide in, a vertical rod connected with each bearing, a weight attached to each rod, a depending frame attached to the bearings, and a treadle controlling the said frame. 85

5. In a reeling-machine for paper or other fabric, the combination with a driving-roll, of a winding-roll surmounted upon the driving-roll and adapted to be rotated thereby, movable bearings in which the winding-roll is mounted, vertical rods connected with the bearings and extending upward therefrom, weights carried by the rods, means for raising the winding-roll and the said rods, and means for regulating the tension of the fabric. 105

In testimony whereof I have signed my name to this specification in the presence of two subscribing witnesses.

WILLIAM HUBELI WALDRON.
